(57) **CLAIM**

The ornamental design for an assembly of stationery clips, as shown and described.

DESCRIPTION

FIG. 1 is a perspective view of an assembly of stationery clips in accordance with my new design;

FIG. 2 is a perspective view of the assembly of stationery clips shown in FIG. 1, wherein an individual stationery clip of the assembly of stationery clips is shown among the remaining stationery clips;

FIG. 3 is a front view of an individual stationery clip of the assembly of stationery clips in FIG. 1, shown without the remainder of the claimed design for convenience;

FIG. 4 is a rear view of the stationery clip shown in FIG. 3; FIG. 5 is a perspective view of the stationery clip shown in FIG. 3;

FIG. 6 is a left side view of the stationery clip shown in FIG. 3;

FIG. 7 is a right side view of the stationery clip shown in FIG. 3;

FIG. 8 is a top view of the stationery clip shown in FIG. 3;

FIG. 9 is a bottom view of the stationery clip shown in FIG. 3; FIG. 10 is a front view of a cover of the assembly of stationery clips in FIG. 1, shown without the remainder of the claimed design for convenience;

FIG. 11 is a rear view of the cover shown in FIG. 10;

FIG. 12 is a perspective view of the cover shown in FIG. 10;

FIG. 13 is a left side view of the cover shown in FIG. 10;

FIG. 14 is a right side view of the cover shown in FIG. 10;

FIG. 15 is a top view of the cover shown in FIG. 10; and,

FIG. 16 is a bottom view of the cover shown in FIG. 10.

The long and short broken lines around the inside edge of the individual stationery clip and cover define the bounds of the claimed design and form no part thereof.

The evenly spaced broken lines showing the ring and the U-shaped features and apertures in one end and the aperture in the corner of the other end of the individual clips and the aperture in the cover are included to show portions that form no part of the claimed design.
